The ornamental design for a vehicle tire tread, as shown and described.

DESCRIPTION

FIG. 1 is an outside perspective view of our new vehicle tire tread design, it being understood that the depicted tread pattern extends over the entire circumference of the tire; FIG. 2 is a front elevational view thereof, the rear elevational view being identical;

FIG. 3 is an outside elevational view thereof, the inside elevational view being identical;

FIG. 4 is a top view thereof, the bottom view being identical;

FIG. 5 is an outside perspective view of a second embodiment of the tire tread design shown in FIGS. 1-4; and,

FIG. 6 is an outside elevational view of the tire tread design shown in FIG. 5, the inside elevational view being identical. In the drawing figures, the tire features shown in broken lines indicate environmental subject matter only, and form no part of the claimed design.
